UNITED STATES PATENT OFFICE.

SAMUEL E. POOLE, OF RANDOLPH, OHIO.

STARTING MEANS FOR EXPLOSIVE-ENGINES.

SPECIFICATION forming part of Letters Patent No. 708,463, dated July 1, 1902.

Application filed January 26, 1902. Serial No. 91,211. (No model.)

To all whom it may concern:

Be it known that I, SAMUEL E. POOLE, a citizen of the United States, residing at Randolph, in the county of Portage and State of Ohio, have invented certain new and useful Improvements in Starting Means for Explosive-Engines; and I do hereby declare the following to be a full, clear, and exact description of the invention, such as will enable others skilled in the art to which it appertains to make and use the same, reference being had to the accompanying drawing, and to the figures of reference marked thereon, which from part of this specification.

15 My invention relates to gas or gasoline engines, and is designed to obviate the difficulty heretofore experienced in starting such engines. It embodies the idea of heating the cylinder before starting the engine, so that 20 generation of the gas is assisted and condensation thereof prevented; also, the operation of the sparkers materially improved. Such engines commonly have a cylinder and a jacket surrounding the same, through which 25 cooling-water circulates to absorb the heat caused by the explosions. In cold weather to avoid freezing of the water and bursting the jacket the water has to be drawn off when the engine is stopped, and after the engine 30 gets cold considerable difficulty is experienced in starting it again, both because the gas condenses or does not readily generate in a cold engine and also because the ignition by the sparkers is uncertain and 35 difficult when the parts are cold. Such engines are usually started by hand or by an auxiliary starting apparatus, and it often requires a long time, frequently amounting to hours in very cold weather, before the engine 40 "warms up" enough to run itself. When the engine is cold, a very strong electric current is required to produce the necessary ignition, and then when the engine becomes warm such current is too strong, resulting in 45 burning out the electrodes or platinum points.

These defects impair the utility of such engines, especially in cold weather or climates, and are annoying and expensive and also attended with considerable danger.

It is the object of my invention to remedy 50 these defects by a preliminary heating of the cylinder and adjacents parts by means of steam introduced into the jacket-space ordinarily occupied by the cooling-water.

In the drawing the figure is a sectional 55 view of a construction embodying my invention.

The cylinder is indicated at 6, having a jacket 7 with a space between (indicated at 8) tapped by inlet and outlet water-pipes 9 60 and 10, through which water for cooling the cylinder circulates. In addition to these parts I provide a steam-pipe 11, which also communicates with the space 8. The pipe is provided with a stop-cock 12. Steam may be 65 supplied from any boiler or steam-generator.

In operation, the jacket being empty and the parts cold, steam is admitted within the jacket until the cylinder and the adjacent parts are sufficiently warm. Then the engine 70 may be started with one or two turns of the fly-wheel, and evaporation or generation of the gasoline will be materially assisted, as well as the operation of the sparking devices. When the engine reaches sufficient speed to 75 warm itself, the steam is turned off and the cooling-water allowed to circulate in the jacket, as usual.

What I claim is—

In a gas or gasoline engine, in combination, 80 a cylinder and its jacket, a pipe for introducing a cooling medium into the jacket, and a pipe for introducing a heating medium into the jacket.

In testimony whereof I affix my signature 85 in presence of two witnesses.

SAMUEL E. POOLE.
